CONVERSION OF HYDROCARBON OILS

Kenneth Swartwood, Chicago, Ill., assignor to
 Universal Oil Products Company, Chicago, Ill.,
 a corporation of Delaware

Application March 26, 1936, Serial No. 70,927

10 Claims. (Cl. 196—49)

This invention particularly refers to an improved process for the fractional distillation of hydrocarbon oils accompanied by selective pyrolytic conversion of intermediate fractions of the 5 charging stock and intermediate liquid conversion products of the process and further conversion of the residual liquid products from the distilling and cracking operations to produce either good quality fuel oil or coke.

One specific embodiment of the invention comprises subjecting relatively heavy intermediate liquid conversion products of the process to conversion conditions of cracking temperature and superatmospheric pressure in a heating coil 10 and communicating enlarged reaction chamber, separating the resulting vaporous and liquid conversion products, subjecting the latter to further vaporization in a zone of substantially reduced pressure relative to that employed in the reaction chamber, subjecting the vaporous conversion products to fractionation whereby their insufficiently converted components are condensed as reflux condensate and separated into selected relatively low-boiling and high-boiling fractions, supplying the latter to the heating coil for said conversion, subjecting fractionated vapors of the desired end-boiling point to condensation, recovering the resulting distillate, subjecting said low-boiling fractions of the reflux 15 condensate to independently controlled conversion conditions of cracking temperature and superatmospheric pressure in a separate heating coil, introducing the heated products from said separate heating coil into a separate vaporizing and fractionating zone, supplying hydrocarbon oil charging stock for the process to said separate vaporizing and fractionating zone wherein it commingles with the heated products from said separate heating coil and is subjected to 20 vaporization and fractionation, returning selected intermediate fractions of the materials supplied to said separate vaporizing and fractionating zone to said separate heating coil for further conversion, subjecting fractionated vapors of the desired end-boiling point from said separate vaporizing and fractionating zone to condensation, recovering the resulting distillate, subjecting residual liquid products from said reduced pressure vaporizing zone and from said 25 separate vaporizing and fractionating zone to further conversion in another separate heating coil, separating the resulting vaporous and non-vaporous products and supplying the former to said reduced pressure vaporizing zone.

By this method of operation the excess heat

in the products from the relatively light oil cracking coil is utilized for the useful purpose of effecting distillation of the charging stock, the charging stock in turn serving to cool the heated products sufficiently to prevent excessive further conversion thereof. Any desirable low-boiling fractions of the charging stock, such as materials within the boiling range of motor fuel and of satisfactory antiknock value, are recovered from the distillation step together with the 5 motor fuel product of the relatively light oil cracking operation while other selected low-boiling or intermediate fractions of the charging stock are subjected to conversion together with selected relatively low-boiling intermediate fractions of the conversion products from both the light oil and heavy oil cracking operations. Any high-boiling fractions of the charging stock unsuitable for conversion with the selected intermediate fractions from the distilling and light oil cracking step are subjected, together with residual liquid from both the light oil and heavy oil cracking operations, to conversion under relatively mild cracking conditions in a separate heating coil wherein conditions of operation may be regulated to produce from the residual liquid either relatively dry coke or a liquid residue of improved characteristics suitable for sale as fuel oil.

The accompanying diagrammatic drawing illustrates one specific form of apparatus embodying the features of the invention.

Referring to the drawing, heating coil 1 to which relatively heavy intermediate liquid conversion products of the process are supplied, in the manner to be later described, is located within a furnace 2 which supplies the required heat to the oil passing through the heating coil to subject the same to the desired conversion temperature, preferably at a substantial superatmospheric pressure. Hot conversion products from heating coil 1 are discharged through line 3 and valve 4 into reaction chamber 5.

Chamber 5 is also preferably maintained at a substantial superatmospheric pressure and, although not indicated in the drawing, is preferably insulated in order that conversion of the heated products supplied to this zone, and particularly their vaporous components, may continue therein. In the particular case here illustrated, both vaporous and residual liquid products are discharged in commingled state from the lower portion of chamber 5 through line 6 and valve 7 into vaporizing and separating chamber 8. It is, however, also within the scope of 55

- the invention, when desired, to separately remove vaporous and liquid conversion products from chamber 5, in which case the liquid products are directed to chamber 8, in the manner 5 described, while vaporous products separately removed from the chamber at any desired point therein may be directed by well known means, not illustrated, either to chamber 8 or to fractionator 12 or, in part, to both zones.
- 10 Chamber 8 is preferably maintained at a substantially reduced pressure relative to that employed in the reaction chamber by means of which appreciable further vaporization of the liquid conversion products supplied to this zone 15 is accomplished. Separation of vapors and non-vaporous residual liquid is accomplished in chamber 8, the latter being removed from the lower portion of this zone through line 9 and directed therefrom to cooling and storage or to further 20 treatment, as will be later described, while vaporous products are withdrawn from the upper portion of chamber 8 and directed through line 10 and valve 11 to fractionation in fractionator 12.
- 25 The vaporous products supplied to fractionator 12, boiling above the range of the desired light distillate product of this stage of the system are condensed in the fractionator as reflux condensate which may, when desired, be withdrawn from 30 the lower portion of this zone through line 13 and valve 14 to pump 15 by means of which it is returned through line 16 and valve 17 to conversion, as previously described, in heating coil 1. Preferably, however, the reflux condensate formed 35 in fractionator 12 is separated into selected relatively low-boiling and high-boiling fractions, in which case only the high-boiling fractions are returned from the lower portion of the fractionator, as described, to conversion in heating coil 40 1 while the low-boiling fractions are removed from one or a plurality of suitable intermediate points in the fractionator and directed to separate further conversion. In the case here illustrated, a selected low-boiling fraction of the 45 reflux condensate is removed from fractionator 12 through line 18 and valve 19 to pump 20 by means of which it is supplied through line 21 and valve 22 to conversion in heating coil 23, as will be later more fully described.
- 50 Fractionated vapors of the desired end-boiling point are withdrawn, together with uncondensable gas, from the upper portion of fractionator 12 through line 27 and valve 28 and are subjected to condensation and cooling in condenser 29. The 55 resulting distillate and gas passes through line 30 and valve 31 to collection and separation in receiver 32. Uncondensed gases are released from the receiver through line 33 and valve 34. Distillate is withdrawn from receiver 32 through line 60 35 and valve 36 to storage or to any desired further treatment. When desired, regulated quantities of the distillate collected in receiver 32 may be recirculated by well known means, not illustrated in the drawing, to the upper portion of 65 fractionator 12 to serve as a refluxing and cooling medium in this zone for assisting fractionation of the vapors and to maintain the desired vapor outlet temperature therefrom.
- The oil supplied to heating coil 23 from fractionator 12, and/or other sources which will be 70 later described, is subjected therein, by means of heat supplied from a furnace 24, to the desired conversion temperature, preferably at a substantial superatmospheric pressure, and the heated 75 products are discharged from heating coil 23
- through line 25 and valve 26 into the lower portion 37 of distilling and fractionating column 39. Preferably, the heated products are cooled, prior to their introduction into column 39, sufficiently to prevent excessive further conversion thereof 5 in this zone. This may be accomplished, at least in part, by substantially reducing the pressure imposed upon the stream of heated oil as it passes through valve 26 and, when desired, other means of cooling the stream of hot conversion products 10 may be employed and one such means will be later described.
- The lower portion 37 of column 39 comprises a vaporizing and separating chamber to which charging stock for the process, as well as the 15 heated products from heating coil 23, are supplied, whereby the charging stock is subjected to vaporization by means of the excess heat in the hot conversion products discharged from the heating coil and the vaporous components thereof, subjected to subsequent fractionation, together with the vaporous products with which they are commingled. Charging stock is supplied through line 49 and valve 41 to pump 42 by means of which it is fed through line 43 and 25 may be introduced directly into chamber 37 by means of line 44 and valve 45 or it may be introduced, all or in part, through line 46 and valve 47 into line 25, wherein it commingles with the stream of heated products from heating coil 23 30 and serves to cool the same, the commingled oils being introduced into chamber 37.
- The components of the charging stock vaporized by contact with the heated products from heating coil 23 and the components of the conversion products which remain in vaporous state in chamber 37 are directed through a suitable partition 48 into the upper portion 38 of column 39 which comprises a fractionating zone wherein the components of the vapors boiling above the end-boiling point of the desired light distillate product of this stage of the process are condensed as reflux condensate. The reflux condensate formed in fractionator 38 is withdrawn therefrom through line 49 and valve 50 to pump 51 by 45 means of which it is fed through line 52 and valve 53 into line 22 and directed therefrom to heating coil 23 for conversion, either alone or together with the low-boiling reflux condensate from fractionator 12. 50
- Fractionated vapors of the desired end-boiling point are withdrawn, together with uncondensable gas, from the upper portion of fractionator 38, and directed through line 54 and valve 55 to condensation and cooling in condenser 56. The 55 resulting distillate and gas passes through line 57 and valve 58 to collection and separation in receiver 59. Uncondensed gases may be released from the receiver through line 60 and valve 61. Distillate is withdrawn from receiver 59 through line 62 and valve 63 to storage or to any desired 60 further treatment. When desired, regulated quantities of the distillate collected in receiver 59 may be recirculated by well known means, not illustrated in the drawing, to the upper portion of 65 fractionator 38 to serve as a refluxing and cooling medium in this zone for assisting fractionation of the vapors and to maintain the desired vapor outlet temperature therefrom.
- The components of the conversion products, 70 supplied to chamber 37 from heating coil 23, which remain unvaporized in chamber 37 and any high-boiling non-vaporous components of the charging stock are withdrawn from the lower portion of chamber 37 through line 64 and valve 75

65 to pump 66 by means of which this residual liquid is directed through line 67 and valve 68 to conversion in heating coil 69.

Non-vaporous residual liquid withdrawn from 5 chamber 8 through line 9, as previously described, may be removed, all or in part, from the system through line 70 and valve 71 to cooling and storage or elsewhere, as desired, or it may be directed, all or in part, from line 9 through line 72 and 10 valve 73 into chamber 37, wherein it commingles with the liquid products in this zone to be directed therewith, in the manner previously described, to conversion in heating coil 69, or a portion or all of the residual liquid from chamber 15 8 may be diverted from line 9 through line 74 and valve 75 to pump 76 by means of which it is supplied through line 77, valve 78 and line 67 to further conversion in heating coil 69. In case chamber 37 is operated at a higher temperature 20 or a lower pressure than that employed in chamber 8 introduction of the residual liquid from chamber 8 into this zone will serve to effect further vaporization of this material, prior to its introduction into heating coil 69.

25 The relatively high-boiling residual oils supplied, as described, to heating coil 69 are subjected therein to the desired temperature and pressure conditions by means of heat supplied from a furnace 79 and the heated products are 30 discharged from the heating coil through line 80 and valve 81 into chamber 82.

The conditions of operation employed in heating coil 69 and chamber 82 may be regulated to effect subsequent reduction of the residual oils 35 to coke in chamber 82 or a milder type of conversion commonly termed "viscosity breaking" may be employed in heating coil 69 so that the residual product recovered from chamber 82 is a liquid residue of improved characteristics, particularly with respect to viscosity and flash point. The conditions employed in heating coil 69 and 40 chamber 82 may be selected to suit requirements, depending primarily upon the nature of the residual oil supplied to heating coil 69 and the 45 desired type of residual product.

Vaporizing or coking chamber 82 is preferably operated at a substantially reduced pressure relative to that employed at the outlet from heating coil 69, although any desired pressure up to substantially the same as that at the outlet from the heating coil may be utilized in this zone, when desired. When coke is produced in chamber 82 it may be allowed to accumulate therein until the chamber is substantially filled or until its 55 operation is completed for any other reason and, when desired, a plurality of similar coking chambers may be employed, although only one is illustrated in the drawing. When liquid residue is produced in chamber 82 it may be removed from the lower portion of this zone through line 83 and valve 84 to cooling and storage or elsewhere, as desired, and this line may also serve as a drain-line and, particularly when the chamber is operated as a coking zone, steam, water or any other suitable cooling material may be introduced 60 into the coking chamber through line 83 and valve 84 to hasten cooling and facilitate the removal of coke from this zone after its operation has been completed and after it has been isolated from the rest of the system. Vaporous products are removed from the upper portion of chamber 65 82 and directed through line 85 and valve 86 to chamber 8 or they may, when desired, be supplied, by well known means not illustrated, either 70 to chamber 37 or to fractionator 12.

The preferred range of operating conditions which the present process may employ to accomplish the desired results, in an apparatus such as illustrated and above described, may be approximately as follows: The heating coil to which the total reflux condensate from the fractionator of the first mentioned cracking stage or high-boiling fractions of the reflux condensate from this state are supplied may utilize an outlet conversion temperature ranging for example, from 5 850 to 975° F., preferably with a superatmospheric pressure at this point in the system of from 100 to 500 pounds, or more, per square inch. The succeeding reaction chamber may employ a superatmospheric pressure substantially the same or 10 lower than that utilized at the outlet from the heating coil. The vaporizing and separating chamber of this stage of the system preferably employs a substantially reduced pressure, relative to that utilized in the reaction chamber, 15 ranging, for example, from a superatmospheric pressure of 100 pounds, or thereabouts, per square inch down to substantially atmospheric pressure and the pressure employed in this zone may be substantially equalized or reduced in the succeeding fractionating, condensing and collecting equipment. The heating coil to which reflux condensate from the distilling and fractionating column is supplied, either alone or together with light reflux condensate from the fractionator of 20 the first mentioned cracking stage, preferably employs an outlet conversion temperature of the order of 900 to 1050° F. with any desired pressure from substantially atmospheric to a superatmospheric pressure of 800 pounds, or more, per 25 square inch, relatively low superatmospheric pressure normally being employed when temperatures of the order of 1000° F., or higher are utilized. The distilling and fractionating column to which the charging stock and the conversion 30 products from the light oil heating coil are supplied preferably employs a relatively low pressure of the order of 100 pounds per square inch superatmospheric down to substantially atmospheric pressure, although higher pressures up to substantially 35 the same as that employed at the outlet from the communicating heating coil may be utilized in this zone, when desired. When the process is operated for the production of coke as the final residual product the temperature 40 employed in the heating coil of the coking stage may range, for example, from 900 to 1050° F., preferably with a superatmospheric pressure in this zone of from 50 to 150 pounds or more per square inch and with a relatively short time factor 45 in the heating coil in order to preclude any substantial formation and deposition of coke, prior to the introduction of the heated products into the coking chamber. When a viscosity breaking operation is employed in the heating coil to 50 which the residual liquids are supplied the temperature at the outlet therefrom may range, for example, from 775 to 875° F., preferably with a superatmospheric pressure at this point in the system of from 100 to 250 pounds, or thereabouts, 55 per square inch. The vaporizing or coking chamber, as previously mentioned, may employ any desired pressure ranging from substantially the same as that employed at the outlet from the communicating heating coil down to substantially 60 atmospheric pressure.

The following is a specific example of the operation of the process as it may be accomplished in an apparatus such as illustrated and above described. The example, however, typifies only 75

one embodiment of the invention and is not to be construed as limiting the various embodiments of the process disclosed. The charging stock is a mixed base crude of approximately 37° A. P. I. 5 gravity which contains approximately 25 per cent of materials boiling up to 387° F. which are of satisfactory antiknock value for blending with the motor fuel products of the light oil cracking operation. A major portion of the charging stock 10 is commingled with the heated products from the light oil cracking coil, prior to their introduction into the distilling and fractionating column and the remainder is supplied directly to the lower portion of this zone. High-boiling fractions of 15 the reflux condensate from the fractionator of the first cracking stage of the system are subjected in the heating coil to which this material is supplied to an outlet conversion temperature of approximately 930° F. at a superatmospheric 20 pressure of about 300 pounds per square inch. This pressure is substantially equalized in the succeeding reaction chamber and is reduced in the vaporizing chamber, to which both liquid and vaporous conversion products from the reaction 25 chamber are supplied, to a superatmospheric pressure of approximately 50 pounds per square inch. This pressure is substantially equalized in the succeeding fractionating, condensing and collecting portions of the first cracking stage. A 30 motor fuel product of approximately 400° F. end-boiling point is recovered from this stage of the system and low-boiling reflux condensate from the fractionator of this stage, having a boiling range of approximately 380 to 525° F., is supplied, 35 together with reflux condensate from the distilling and fractionating column, to the light oil cracking coil wherein those materials are subjected to an outlet conversion temperature of approximately 950° F. at a superatmospheric pressure of approximately 500 pounds per square inch. The distilling and fractionating column is operated at a superatmospheric pressure of approximately 75 pounds per square inch and the conversion products supplied thereto from the 40 light oil heating coil are cooled, prior to their introduction into this zone, to approximately 785° F. A motor fuel product comprising straight-run and cracked products having an end-boiling point of approximately 385° F. is recovered as 45 the overhead product from the distilling and fractionating column. Residual liquid from the distilling and fractionating column is supplied, together with residual liquid from the vaporizing chamber of the first cracking stage, to a separate 50 heating coil wherein it is quickly heated under non-coking conditions to an outlet conversion temperature of approximately 980° F. at a superatmospheric pressure of approximately 80 pounds per square inch and then introduced into the coking zone which is operated at substantially the 55 same pressure.

An operation such as above described will produce, per barrel of charging stock, approximately 70 per cent of motor fuel of good antiknock quality and approximately 50 pounds of low volatile petroleum coke of uniform quality and good structural strength, the remainder being chargeable, principally, to uncondensable gas.

I claim as my invention:

1. In a process for the pyrolytic conversion of hydrocarbon oils wherein selected intermediate liquid products of the process are subjected to conversion conditions of cracking temperature and superatmospheric pressure, the resulting vapors and residual liquid separated in a reduced

pressure separating zone, the vapors subjected to fractionation for the formation of reflux condensate, fractionated vapors of the desired end-boiling point subjected to condensation, the resulting distillate recovered and reflux condensate formed by said fractionation subjected to said conversion, the improvement which comprises simultaneously introducing hydrocarbon oil charging stock for the process into a distilling and fractionating zone wherein it is subjected to appreciable vaporization by direct contact with hot conversion products supplied to this zone, as hereinafter set forth, and wherein the heavy non-vaporous components of the charging stock commingle with the residual liquid components of said conversion products while the vaporous components of the charging stock are subjected to fractionation in this zone together with the vaporous components of said conversion products, for the formation of reflux condensate, subjecting fractionated vapors of the desired end-boiling point from the distilling and fractionating zone to condensation, recovering the resulting distillate, subjecting reflux condensate formed in the distilling and fractionating zone to independently controlled conversion conditions in a separate cracking zone, introducing the resulting products into the distilling and fractionating zone, subjecting the commingled high-boiling components of the charging stock and residual liquid conversion products, together with residual liquid from the first mentioned cracking operation, to further conversion in another separate cracking zone, separating the resulting vaporous and non-vaporous products, and introducing said vaporous products to said reduced pressure separating zone.

2. In a process for the pyrolytic conversion of hydrocarbon oils wherein selected intermediate liquid products of the process are subjected to conversion conditions of cracking temperature and superatmospheric pressure, the resulting vapors and residual liquid separated in a reduced pressure separating zone, the vapors subjected to fractionation for the formation of reflux condensate, fractionated vapors of the desired end-boiling point subjected to condensation, the resulting distillate recovered and reflux condensate formed by said fractionation subjected to said conversion, the improvement which comprises simultaneously introducing hydrocarbon oil charging stock for the process into a distilling and fractionating zone wherein it is subjected to appreciable vaporization by direct contact with hot conversion products supplied to this zone, as hereinafter set forth, and wherein the heavy non-vaporous components of the charging stock commingle with the residual liquid components of said conversion products while the vaporous components of the charging stock are subjected to fractionation in this zone, together with the vaporous components of said conversion products, for the formation of reflux condensate, subjecting fractionated vapors of the desired end-boiling point from the distilling and fractionating zone to condensation, recovering the resulting distillate, subjecting reflux condensate formed in the distilling and fractionating zone to independently controlled conversion conditions in a separate cracking zone, introducing the resulting products into the distilling and fractionating zone, subjecting the commingled high-boiling components of the charging stock and residual liquid conversion products, together with residual liquid from the first mentioned cracking opera- 75

tion, to further conversion in another separate cracking zone, and fractionating resultant vapors in admixture with vapors separated in said reduced pressure separating zone.

5 3. A process such as claimed in claim 1 wherein in the reflux condensate formed by said fractionation of the vapors of the first mentioned cracking operation is separated into selected relatively low-boiling and high-boiling fractions, the 10 high-boiling fractions subjected to the first mentioned cracking operation and the low-boiling fractions subjected to cracking together with said reflux condensate from the distilling and fractionating zone.

15 4. A process such as claimed in claim 2 wherein the reflux condensate formed by said fractionation of the vaporous conversion products of the first mentioned cracking operation is separated into selected relatively low-boiling and high-boiling fractions, the high-boiling fractions subjected to the first mentioned cracking operation and the low-boiling fractions subjected to cracking together with said reflux condensate from the distilling and fractionating zone.

20 5. In a process for the pyrolytic conversion of hydrocarbon oils wherein selected intermediate liquid products of the process are subjected to conversion conditions of cracking temperature and superatmospheric pressure in a heating coil 25 and communicating enlarged reaction chamber, the resulting vaporous and liquid conversion products separated, the vaporous conversion products subjected to fractionation for the formation of reflux condensate, fractionated vapors 30 of the desired end-boiling point subjected to condensation, the resulting distillate recovered, said reflux condensate separated into selected relatively low-boiling and high-boiling fractions, the latter supplied for further cracking to said heating coil, said low-boiling fractions subjected to 35 independently controlled conversion conditions of cracking temperature and superatmospheric pressure in a separate heating coil, the resulting heated products cooled to a temperature sufficient 40 to prevent excessive further cracking thereof and introduced into a separate vaporizing and separating chamber, the improvement which comprises introducing hydrocarbon oil charging stock for the process into said separate 45 vaporizing and separating chamber, subjecting 50 the vaporous products therefrom, including

vaporous components of the charging stock, to fractionation, subjecting fractionated vapors of the desired end-boiling point from the last mentioned fractionating step to condensation, recovering the resulting distillate, returning reflux 5 condensate formed in the last mentioned fractionating step to cracking in said separate heating coil, removing residual liquid, including high-boiling non-vaporous components of the charging stock and residual liquid conversion products 10 formed in the last mentioned cracking operation, from said separate vaporizing and separating chamber, subjecting the same to independently controlled conversion conditions of cracking temperature and superatmospheric pressure in another separate heating coil, introducing the heated products into a separate chamber wherein in their vaporous and non-vaporous components are separated, and commingling the vaporous products from the last mentioned chamber with 15 the first-mentioned vaporous conversion products 20 of the process prior to fractionation of the latter.

6. A process such as claimed in claim 5 wherein liquid conversion products of the first mentioned cracking operation are also supplied for further conversion to the last mentioned heating coil.

7. A process such as claimed in claim 5 wherein in charging stock for the process is commingled 30 with the hot conversion products discharged from the second mentioned heating coil prior to their introduction into said separate vaporizing and separating chamber.

8. A process such as claimed in claim 5 wherein in the liquid conversion products of the first mentioned cracking operation are introduced into said separate vaporizing and separating chamber.

9. A process such as claimed in claim 5 wherein substantially dry coke is recovered in said separate chamber as the residual product of the last mentioned cracking operation.

10. A process such as claimed in claim 5 wherein in the residual product recovered from the last mentioned cracking operation comprises liquid residue of improved characteristics relative to the residual liquids supplied to the last mentioned heating coil.

50 KENNETH SWARTWOOD.
